FRUIT BASKET PACKING DEVICE

John S. Anderson, Ontario, Oreg.

Application March 21, 1939, Serial No. 263,308

2 Claims. (Cl. 226—17)

This invention relates to fruit basket packing devices, and has for one of its objects the production of a simple and efficient means for facilitating the moving of the fruit from the packing tub into the basket, without injuring or crushing the fruit.

A further object of this invention is the production of an expansible tub which is so constructed as to expand as the facer plate moves longitudinally of the tub, while the tub is being forced downwardly over the ejector stand.

Other objects and advantages of the present invention will appear throughout the following specification and claims.

In the drawing:

Figure 1 is a side elevational view of the tub; Figure 2 is a top plan view thereof;

Figure 3 is a vertical sectional view taken on line 3—3 of Figure 1;

Figure 4 is a side elevational view of the tub and basket positioned upon the ejector stand, certain parts being shown in section;

Figure 5 is a sectional view taken on line 5—5 of Figure 4.

By referring to the drawing, it will be seen that 10 designates the packing tub which is preferably formed of galvanized iron, steel, or other suitable material. The wall of the packing tub is provided with overlapping ends 11, which overlapping ends are pivotally secured together, as at 12, near the inner end of the tub, as shown in Figure 1. The overlapping ends 11 preferably flare outwardly to become wider at the outer end of the tub than at the inner end, as shown clearly in Figure 1. The inner end of the tub is provided with an outwardly inclined flange 13 which is preferably reinforced by a reinforcing plate 14, the plate 14 being held in position by a rolled rim portion 15. A plurality of longitudinally extending straps 16 are secured to one side of the tub 10 and upon the outer face of the wall thereof, and a plurality of longitudinally extending straps 17 are secured to the opposite side of the tub 10 upon the outer face of the wall thereof, and these straps 17 are arranged on opposite sides of the overlapping ends 11 of the tub. These longitudinally extending straps 16 and 17 are provided with laterally extending basket-supporting feet 18, which feet 18 are spaced inwardly with respect to the outer edge 19 of the tub 10. Lugs 20 are secured to the straps 17 near their outer ends adjacent the feet 18, and a tension coil spring 21 is secured at its opposite ends to the opposite lugs 20, and this spring 21 spans or overlies the overlapping ends 11 of the wall of the tub. A shield

or guard plate 22 is secured, as at 23, to one of the walls and overlies the overlapping ends 11, as shown in detail in Figure 5; and this shield plate 22 is provided with parallel flanges 24 running longitudinally of the plate to provide a shielding panel for holding the tension coil spring 21 against lateral displacement.

In connection with my invention, I also employ an extension collar 25 which is adapted to fit within the inner end of the tub 10, as shown in detail in Figures 3 and 4, which collar 25 comprises a circular band having a rolled flange 26 along one edge for receiving an outwardly inclined supporting flange 27, which flange in turn is provided with a rolled or beaded edge 28. This outwardly inclined flange 27 is adapted to constitute a rest for the flange 13 of the tub when the tub 10 is placed upon the collar 25. This collar 25 is provided with suitable hand-holds or apertures 29 near the bottom edge 30 thereof, and a suitable facer plate 31 is adapted to be slidably mounted through the collar 25 and the tub 10. The facer plate 31 is provided with a depending flange 32 of sufficient depth to support the edges 33 of the facer plate normally just above the hand-holds 29, as shown in Figure 3 so that the operator may stick his fingers through the holds 29 and support the edges 33 of the plate 31 while moving the tub to a position upon the ejector stand 34 of the conventional type. This collar 25 will efficiently support the tub 10 in a proper position where it may be conveniently lifted from the table or the floor to the ejector stand.

The operation of the device is as follows:

The tub 10 and collar 25 are lifted from the floor, table or other support to a position upon the ejector stand 34, as shown in Figure 4. The facer plate 31 rests upon the upper end of the ejector stand 34 in the conventional manner, thereby supporting the tub 10 in the position shown in Figure 4. The basket B is then placed over the upper end of the tub 10 in an inverted position, the outer edge of the basket resting upon the supporting feet 18 of the respective straps 16 and 17. As the basket B is pushed downwardly, the tub 10 in turn is forced downwardly over the ejector stand 34 and the facer plate 31 will move upwardly through the length of the tub 10 and will spread the upper end of the tapering tub outwardly against the tension of the spring 21 thereby preventing the fruit from becoming crushed, marred or injured due to the tapering nature of the wall of the tub. The pressure of the fruit also will assist in spreading

35

55

the wall of the tub. The spring 21 is of sufficient tension to yield sufficiently as the facer plate 31 moves longitudinally, and in this way the fruit will be easily and conveniently ejected from the 5 tub 10 without compression resistance. The tension of the spring 21 will normally hold the fruit in a firm compact condition, but at the same time will sufficiently yield to allow the outer end 10 of the tub to increase in diameter as the facer plate 31 is moved longitudinally. In this way, the fruit will be forced into the basket B with a minimum amount of danger of injury to the fruit.

Having described the invention, what is claimed is:

- 15 1. A fruit basket packing device comprising a tub having an expansible tapering outer end and an enlarged inner end, the wall of the tub having overlapping portions, means for pivotally connecting the overlapping portions near the inner 20 end of the tub, the overlapping portions of the tub being adapted to slide one over the other for increasing the diameter of the outer end of the tub, a spring spanning the overlapping portions adjacent the expansible tapering end for yield- 25 ably holding the tapering end against expansion, a guard plate secured to the outer face of the wall of the tub and overlying the overlapping ends thereof, the guard plate having parallel

spaced flanges to provide a spring-receiving channel, and said spring being adapted to fit longitudinally within said channel, in a manner whereby the overlapping edges of the tub will be prevented from pinching and cutting the spring as the tub contracts. 5

2. A fruit basket packing device comprising a tub having an expansible tapering outer end and an enlarged inner end, the wall of the tub having overlapping portions, means for connecting the overlapping portions near the inner end of the tub, the overlapping portions of the tub being adapted to slide one over the other for increasing and decreasing the diameter of the outer end of the tub, a spring guard plate secured to the outer face of the wall of the tub at one end, and the other end of the guard plate overhanging the overlapping ends of the walls of the tub, a spring spanning the overlapping portions adjacent the expansible tapering end and secured to the walls of the tub at its opposite ends at points beyond the overlapping portions of the walls for yieldably holding the tapering end against expansion, and said spring overlying the guard plate in a manner whereby the overlapping edges of the tub will be guarded from pinching and cutting the spring as the tub contracts. 10 15 20 25
